MOLDING MACHINE

George Walther, near Dayton, Ohio, assignor to The Dayton Steel Foundry Company, Dayton, Ohio, a corporation of Ohio

Application May 1, 1937, Serial No. 140,212

5 Claims. (Cl. 22—163)

This invention relates to new and useful improvements in molding machines.

It is one of the principal objects of my invention to provide a molding machine in which a sand mold produced by a sand-slinger operation for making castings such as brake drums having cooling fins, may be produced without a dry sand core. Conventionally, when such molds are made, a dry sand core having these fins is set in the mold. However, my means for contracting that pattern after the mold is made makes the core unnecessary, since it enables the pattern to be lowered without breaking the fin-forming cavities.

Other important and incidental objects will be brought out in the following specification and particularly set forth in the subjoined claims.

In the accompanying drawing illustrating one form of embodiment of my invention, Figure 1 is a side view of a molding machine containing my contractible cope pattern. Figure 2 is a top plan view of the contractible pattern and the removable operating unit therefor. And Figure 3 is a perspective view of the holder for the pattern and its operating mechanism.

Referring to the accompanying drawing for a detailed description of the form of embodiment of my invention, disclosed therein, the numeral 1 designates the frame of a molding machine having bottom side members 2 upon which bearing brackets 3 are mounted. These brackets are mounted in two pairs, one at each end of the machine to support two transverse shafts 4, 4.

Secured to each shaft 4 are two end links 5 that are pivotally connected by pins 6 to links 7. The upper ends of the links 7 are pivotally secured to brackets 8 attached to the under side of a pattern plate 9.

Mounted upon the central portion of the pattern plate 9 is a spacer such as the disc casting 10 from which ribs 11 project upwardly to support a similar disc casting 12. This disc 12 is secured to the under side of the middle portion of the pattern top plate 13, within a space defined by an annular rib 14 on the latter.

Slidable between the pattern top plate 13 and the bottom plate 9, within guides in the latter, are segmental sections 16 and 16^a having outwardly projecting fin-forming ribs 17. These segmental sections form together an annular wall around which sand is packed within an enclosing flask 18. While I have shown four of these segmental sections, a greater or a less number may be employed.

For the purpose of lowering the pattern without breaking the fin-forming cavities of the mold,

I provide the following means for pulling the segmental sections inwardly before the pattern is drawn by the handle 19 secured to one of the shafts 4. Formed on the inner peripheral portion of each segmental section is a lug 20 to which one end of a link 21 is pivotally attached. The other end of each link 21 is pivotally secured to one arm 22 of a wrist plate 23 having a hub 24 secured to a vertical shaft 25. The latter is removably journaled in the lower and upper pattern plates 9 and 13. This shaft 25 and its operating connections such as the wrist plate and link, may be removed as a unit and inserted in another machine of the same construction. Attached to the lower end of the shaft 25 is a handle 26 by means of which the shaft may be rotated to draw the segmental sections inwardly a sufficient distance to permit the annular ribs 17 to clear the cavities which they form in the sand mold.

While I have shown a wrist plate and link mechanism for operating the segmental pattern sections 16 and 16^a, cam, fluid or other suitable means may be employed for this purpose without departing from the spirit of the invention.

The inward movement of the segmental sections is made possible by forming elongated slots 27 in the links 21 which actuate the segmental sections 16^a, 16^a. The lugs 20 on these sections carry pins 28 which enter the slots 27 in their respective links. Such a pin and slot connection between the lugs and these links permit the latter to draw segmental sections 16^a, 16^a inwardly only after their ends are cleared by the inwardly moving segmental sections 16, 16.

In order to spread the segmental sections 16^a, 16^a a sufficient distance to permit the other sections 16, 16 to move outwardly between them when it is desired to form a new mold, compression springs 29 may be interposed between lugs 40 on the segmental sections 16^a.

In operation, after a mold has been formed, the shaft 25 is turned by the handle 26 to draw the segmental sections inwardly, first the sections 16, 16 and then the sections 16^a, 16^a, until the ribs 17 on all of the sections clear the cavities which they have formed in the sand mold. The handle 19 is then actuated to draw the pattern downwardly out of the mold without breaking those cavities.

Having described my invention, I claim:

1. A machine for simultaneously forming a mold and grooves therein comprising a frame, a pattern plate, means within said frame for raising and lowering said plate, a pattern com-

- prising peripherally-ribbed segmental sections inwardly and outwardly movable on said plate, a flask on said frame over said sections against which green sand is adapted to be rammed after they are moved outwardly, a vertical operating shaft carried by said plate, a wrist plate fixed to said shaft, links connected between said wrist plate and the segmental sections, and means for turning said shaft to draw the segmental sections inwardly before they are lowered, to prevent the breaking of the cavities which their peripheral ribs form in the sand mold in the flask.
2. A machine for simultaneously forming a mold and grooves therein comprising a frame, a pattern plate, means within said frame for raising and lowering said plate, a plurality of segmental sections inwardly and outwardly slideable on said plate, circumferential fin-forming projections on the peripheries of said sections, said sections when in their outward positions forming an annular peripherally ribbed pattern, a flask on said frame over said sections against which green sand is adapted to be rammed after they are moved outwardly, a vertical operating shaft carried by said plate, a handle on said shaft for turning the same, a wrist plate secured to said shaft, a lug on the interior surface of each section, a link connected between each arm on said wrist plate and each lug, every other link being formed with an elongated slot in its outer end, and a pin on the lug of the segmental section belonging to a slotted link, fitted in its slot, whereby, when the shaft is turned, the first links will draw their segmental sections inwardly before the slotted links engage the pins to draw in their respective sections.
3. A machine for simultaneously forming a mold and grooves therein comprising a frame, a pattern bottom plate, means in said frame for raising and lowering said plate, a pattern top plate, ribs projecting upwardly from the pat-

tern bottom plate to support the pattern top plate, segmental sections inwardly and outwardly movable over the bottom plate to form in their outer portions an annular pattern against which green sand is adapted to be rammed before it is contracted, a vertical shaft journaled in the middle portions of said plates, a wrist plate on said shaft, and links secured to said wrist plate for radial projection between said ribs for pivotal connection to the segmental sections to draw the latter inwardly before they are lowered, thereby preventing the breaking of the mold in the flask.

4. A machine for simultaneously forming a mold and grooves therein, comprising in combination, a frame, a pattern associated with said frame and comprising peripherally ribbed segmental sections, a flask on said frame, means associated with said pattern for moving the same axially respecting said flask, and means for moving said sections inwardly while said pattern is maintained in a pre-determined position axially respecting said flask, said last-mentioned means comprising an operating member and linkage connecting said member and said sections.

5. A machine for simultaneously forming a mold and grooves therein, comprising in combination, a frame, a pattern associated with said frame and comprising peripherally ribbed segmental sections, a flask on said frame, means associated with said pattern for moving the same axially respecting said flask, and means for moving said sections inwardly comprising an operating member, links pivotally connecting said members and said sections, alternate links being provided with elongated slots, a pin on the segmental section belonging to a slotted link, fitted in its slot, whereby when said member is actuated, certain of said sections will be drawn inwardly before the slotted links engage the pins to draw in their respective sections.

GEORGE WALTHER.
